UNITED STATES PATENT OFFICE.

GOTTLIEB D. ELGES, OF CLINTON, MISSOURI.

DESIGN FOR A CIGAR.

SPECIFICATION forming part of Design No. 16,951, dated October 26, 1886.

Application filed August 30, 1886. Serial No. 212,263. Term of patent 3½ years.

To all whom it may concern:

Be it known that I, GOTTLIEB D. ELGES, a citizen of the United States, residing at Clinton, in the county of Henry and State of Missouri, have invented and produced a new and original Design for Cigars, of which the following is a specification, reference being had to the accompanying drawing, forming part thereof, and which is an elevation of my design.

My design consists in a cigar having a body, A, of cylindrical form, and a mouth end having a tip portion, D, of conoid shape, an inner portion, C, flaring toward the body, and an intermediate portion, B, tapering from the

flaring portion to the tip portion, the whole mouth end being of bell shape, as shown.

I claim as my invention—

The design for cigars herein shown and described, the same consisting of a body, A, having a bell-shaped mouth end formed with inner portion, C, flaring toward the body, tip portion D, of conoid form, and intermediate portion, B, tapering from the flaring portion to the tip portion.

GOTTLIEB D. ELGES.

In presence of—

GEO. H. KNIGHT,
EMIL BERGER.
